UNITED STATES PATENT OFFICE

160,304

COMBINED FIELD GLASS AND PERISCOPE

Delma Crichton, New York, N. Y.

Application August 20, 1949, Serial No. 4,626

Term of patent 3½ years

(Cl. D57—1(5))

To all whom it may concern:

Be it known that I, Delma Crichton, a citizen of the United States of America, residing in New York city, county of New York, and State of New York, have invented a new, original, and ornamental Design for a Combined Field Glass and Periscope, of which the following is a specification, reference being had to the accompanying drawing, forming part thereof, wherein,

Figure 1 is a front perspective view of a combined field glass and periscope showing my new design in open position.

Figure 2 is a front perspective view of the combined field glass and periscope in closed position, and

Figure 3 is a front perspective view thereof

showing the field glass in use without the periscope.

I claim:

The ornamental design for a combined field glass and periscope, substantially as shown.

DELMA CRICHTON.
